UNITED STATES PATENT OFFICE.

ERICH H. LICHTENBERG, OF MILWAUKEE, WISCONSIN, ASSIGNOR TO KOEHRING COMPANY, OF MILWAUKEE, WISCONSIN, A CORPORATION.

FASTENING MEANS FOR TRACTION DEVICES.

Application filed March 21, 1925. Serial No. 17,368.

To all whom it may concern:

Be it known that I, ERICH H. LICHTENBERG, citizen of the United States, residing at Milwaukee, in the county of Milwaukee and State of Wisconsin, have invented certain new and useful Improvements in Fastening Means for Traction Devices, of which the following is a specification.

The present invention has to do with the mounting of machine frames or bodies of portable machines, upon the traction elements of devices by which they are to be supported and rendered movable. The invention involves in its direct application means for so connecting the traction frame, so to speak, such as employed for endless tractors, by which a machine may be supported to travel, with the body frame. Broadly there are at least two traction frames equipped with endless tractors, treads or belts, at opposite sides of the body frame. These tractors are attached to the body frames by means of shafts mounted in suitable bearings on the body frame and passing through the traction frame or frames customarily provided at the opposite ends of the shaft or shafts employed. It has been found that in ordinary assemblage of body and traction frames aforesaid, and the shafts forming the connections between them a certain amount of play exists intermediate the traction frame parts and the body frame parts, due largely to the fact that same are composed of castings and must be assembled with some allowances for inaccuracy in the formation of the associated parts.

The present invention involves a provision of a simple means in the form of a cap or attachment applicable to the ends of the shafts and including wedging or camming parts for forcing the body and traction frames into fairly close abutment so as to avoid the looseness and play above referred to.

A full understanding of the invention, its merits, and construction, will be had upon reference to the accompanying drawings in which:

Figure 1 is a fragmentary sectional view showing portions of the body frame of a large machine and a connected traction frame, and illustrating the wedging device of the invention as used herewith;

Figure 2 is a horizontal sectional view of

a side elevation of certain parts shown in Fig. 1 and illustrating the outside channel member or side of the traction frame in section;

Figure 3 is a vertical sectional view taken about on line 3—3, of Fig. 2;

Figure 4 is a detailed sectional view of the stationary abutment member of the wedge device;

Figure 5 is a side view of the same;

Figure 6 is a plan view of one of the movable abutment members; and

Figure 7 is a side view of the member shown in Figure 6.

Similar reference characters refer to like parts throughout this specification and the drawings.

A in the accompanying drawings denotes a portion of the body frame of a large structure, crane, paver, or heavy machine of that type, and B denotes an integral bearing extension projecting forwardly from said frame at a side thereof and through which the shaft 1 passes. The shaft 1 connects the body frame A with the traction frame C, which traction frame includes the spaced channels 2 and the castings or members 3 at the outer and inner sides of said channels 2 and riveted thereto. The parts of the traction frame C are assembled or fabricated in any well known manner.

The particular form of the body frame A, and the traction frame C, are features immaterial to the present invention.

The means for holding the traction frame C in proper relation to the main body frame A comprises a device applied to the outer end of the shaft 1 as seen in Figure 1, but one of which would be applied to the opposite ends of said shaft in practice. This device is of sectional construction in that it composes an outer relatively stationary wedging head abutment member 4 having a recess 5 in which the extremity of the shaft 1 fits, and formed with side portions 6 provided with apertures 7 and having inclines or cam faces 8 virtually on the inner edges of the side portions. The stationary head or abutment 4 is pinned or otherwise rigidly attached to the shaft 1 as by means of the pin 9 that passes through an opening formed transversely through the shaft 1 and which pin also passes through the apertures 7 of the abutment 4.

For coaction with the abutment 4 the de-

vice now being described includes relatively movable abutment members 10, two of which are used and which are of like formations seen best in Figures 6 and 7. Each member 10 is of curved form and is provided with what may be characterized as a flat side 10^a and an inclined or cam side 10^b. At its ends the member 10 is formed with projections 10^c, provided with openings 10^d therethrough.

The two members 10 are assembled so as to extend partially about the shaft 10 at opposite sides thereof and between the abutment 4 and the adjacent collar member or extension 3 of the traction frame C. Bolts 11 are used to connect the members 10 together, are located at opposite sides of the shaft 1 and the side members and passed through the openings in the projections 10^c previously mentioned. For proper cooperation between the camming or wedging members 10 which are the movable abutments, and the member 4, the cam sides or inclines 10^b are caused to contact with the inclines 8 of the abutment 4. The tightening member of the bolts 11 will necessarily cause a wedging action of the members 10 between the adjacent part 3 and the abutment 4, thus pushing the traction frame and the body frame firmly together so that the inner casting 3 of the traction frame abuts with the bearing member B, and the body and traction frames are assembled without looseness therebetween when a machine of this type is put out from the factory.

If, in the course of time and use of the machine, wear takes place between the parts 3 and B or between the outside member 3 and the parts 10, it is evident that the movable abutments 10 may be tightened up or drawn closer together to eliminate said play or looseness incident to wear.

In order to prevent the axle 1, and the parts 4 and 10, from turning in the bearings provided therefor in the multiplane frame casting 3, the wedging head abutment member 4, formed with lugs 4^a at opposite sides thereof, which lugs fit into recesses 3^a formed in said casting 3. As the casting 3 is riveted to the frame member 2 of the traction frame, and is therefore immovable, it will be obvious that the head or abutment member 4 is prevented from turning. The members 4 being pinned on to the shaft 1, said shaft is also in this manner prevented from turning.

Having thus described my invention, what I claim as new and desire to secure by Letters Patent is:

1. In combination, a body frame, a traction frame, a shaft for supporting and connecting said frames while in adjacent relation, means for holding the body frame and traction frame in close relation to one another when assembled with said shaft, in-

cluding an abutment applied to the shaft, and camming means between said abutment and the traction frame.

2. In combination, a body frame, a traction frame, a shaft for supporting and connecting said frames while in adjacent relation, means for holding the body frame and traction frame in close relation to one another when assembled with said shaft, including an abutment applied to the shaft, and camming means between said abutment and the traction frame, comprising an abutment movable between the above mentioned abutment and the traction frame, and means for actuating said movable abutment. 75

3. In combination, a body frame, a traction frame, a shaft for connecting said frames together and assembled therewith, a relatively stationary abutment on said shaft, and a relatively movable abutment for camming engagement with said relatively stationary abutment, and interposed between it and the traction frame, and means for actuating said relatively movable abutment. 80

4. In combination, a body frame, a traction frame, a shaft for connecting said frame together and assembled therewith, a relatively stationary abutment on said shaft, and a relatively movable abutment for camming engagement with said relatively stationary abutment, and interposed between it and the traction frame, and means for actuating said relatively movable abutment, including a part adjacent to said shaft and having bolt connections with the movable abutment for causing camming movement of the latter between the stationary abutment and the traction frame. 90

5. In combination, a body frame, a traction frame, a shaft assembled so as to connect said frames, and means for holding the traction frame tightly against the body frame including an attachment applied to an end of said shaft, said attachment comprising an outer stationary abutment member fixed to the shaft, relatively movable abutment members between the traction frame and said stationary abutment member, the stationary and movable abutment members having coating inclines forming camming surfaces engaging one another, and fastenings connecting the movable abutment members while disposed on opposite sides of the shaft and adapted to actuate said abutment members for wedging movement between the traction frame and stationary abutment member, substantially as described. 110

6. In combination, a body frame, a traction frame, a shaft for supporting and connecting said frame while in adjacent relation, means for holding the body frame and traction frame in close relation to one another when assembled with said shaft, in-

cluding an abutment applied to the shaft, and camming means between said abutment and the traction frame, and means for interlocking the abutment with the traction frame.

7. In combination, a body frame, a traction frame, a shaft for supporting and connecting said frame while in adjacent relation, means for holding the body frame and 10 traction frame in close relation to one another when assembled with said shaft, in-

cluding an abutment applied to the shaft, and camming means between said abutment and the traction frame, and means for interlocking the abutment with the traction frame, and means for connecting the said abutment with the shaft whereby turning of the latter is prevented. 15

In testimony whereof I affix my signature.

ERICH H. LICHTENBERG.
